EDWARD WIARD, OF LOUISVILLE, KENTUCKY.

Letters Patent No. 90,475, dated May 25, 1869.

IMPROVEMENT IN PLOWS.

The Schedule referred to in these Letters Patent and making part of the same.

To all whom it may concern:

Be it known that I, EDWARD WIARD, of Louisville, in the county of Jefferson, and State of Kentucky, have invented a new and useful Improvement in Plows; and I do hereby declare that the following is a full, clear, and exact description thereof, which will enable others skilled in the art to make and use the same, reference being had to the accompanying drawings, forming part of this specification, in which—
Figure 1 represents a side view of my improved plow; and

Figure 2 is a perspective view of the plowshare.

Similar letters of reference indicate corresponding parts.

This invention relates to a new plow, in which the share is composed of three parts, in such manner that if any one of the parts become destroyed, by wear or otherwise, it can be readily replaced without requiring the whole share to be renewed.

The invention consists chiefly in forming a standard and landside support on the mould-board of the plow, so that the landside can, by means of but one bolt, be securely fastened to the same.

The invention also consists in forming a recess on the under side of the detachable point, so that the same can be fitted upon a projecting rib of the mould-board, to be securely fastened, and to have its surface flush with that of the said mould-board.

The invention further consists in forming a hook on the landside, said hook fitting over the support formed on the mould-board, to serve as a fastening-device, so that but one bolt need be used to fasten the landside.

A, in the drawing, represents a plow-beam of suitable kind.

B is the plow-standard. It is cast or formed in one piece with the mould-board C, as is clearly shown in fig. 2.

As a continuation of the standard is also formed on

the mould-board a flange, D, which is somewhat withdrawn from the edge of the mould-board, to allow the landside E to be placed upon it, as shown, so that the landside will be flush with the edge of the mould-board, as indicated in fig. 1.

On the landside is formed a hook, a, which catches over the edge of the flange, or support D, as in fig. 2.

By the use of this hook the fastening of the landside is simplified, so that but one bolt, or screw b, is required to secure it to the flange D.

The plow point G is provided with a notch or recess on its under side, at the back end, so that it may be fitted over a flange or rib, c, projecting from the mould-board, and be fastened by means of a bolt, d.

The handle F is fastened to the landside by a bolt, e, and rests on a step, f, formed thereon.

The mould-board handle is secured to lugs g, g, formed on the mould-board.

A brace may be put between the mould-board and landside, by being fitted with one end in a socket formed on the mould-board, while the other end is placed at the end of a groove or trough formed on the landside, and locked by the end of the handle F in its rear.

The flange D can be readily cast in a simple two-part flask, by receiving a slight taper, so that it could be readily withdrawn from the sand.

Having thus described my invention,

I claim as new, and desire to secure by Letters Patent—

The standard B, mould-board C, and recessed landside-support D, all cast in one piece, in combination with the landside E, when secured to the recessed support D by means of the hook a and single bolt b, all arranged as described, for the purpose specified.

Witnesses: EDWARD WIARD.
